(57) CLAIM

The ornamental design for a modular grate arrangement for a gas cooking appliance, as shown and described.

DESCRIPTION

FIG. 1 is a top right perspective view of a modular grate arrangement for a gas cooking appliance, showing our new design;

FIG. 2 is a top plan view of left side portion of the modular grate of the invention, shown separately for clarity of illustration, with the right side portion being a mirror image thereof;

FIG. 3 is a front elevational view of the left side portion of the modular grate of FIG. 2; and

FIG. 4 is a rear elevational view of the left side portion of the modular grate of FIG. 2;

FIG. 5 is a right elevational view of the left side portion of the modular grate of FIG. 2;

FIG. 6 is a left elevational view of the left side portion of the modular grate portion of FIG. 2;

FIG. 7 is a bottom plan view of the left side portion of the modular grate portion of FIG. 2;

FIG. 8 is a top plan view of the central grate portion of the modular grate of the invention, shown separately for clarity of illustration;

FIG. 9 is a front elevational view of the central grate portion of FIG. 8;

FIG. 10 is a rear elevational view of the central grate portion of FIG. 8;

FIG. 11 is a right elevational view of the central grate portion of FIG. 8, with the left elevational view being a mirror image thereof; and

FIG. 12 is a bottom plan view of the central grate portion of FIG. 8.

The broken lines in FIG. 1 showing gas valve control knobs and a cooktop are for illustrative purposes only and form no part of the claimed invention.
